UNITED STATES PATENT OFFICE.

JOSEPH PANTALEONE AND MICHAEL ZODA, OF TRENTON, NEW JERSEY.

SIDEWALK SNOW-SWEEPER.

1,393,640.

Specification of Letters Patent.

Patented Oct. 11, 1921.

Application filed November 5, 1920. Serial No. 422,106.

To all whom it may concern:

Be it known that we, JOSEPH PANTALEONE and MICHAEL ZODA, both citizens of the United States, and both residents of Trenton, in the county of Mercer and State of New Jersey, have invented a new and Improved Sidewalk Snow-Sweeper, of which the following is a full, clear, and exact description.

10 Our invention relates to a street cleaner, and aims to provide a device of this nature, more particularly adapted for use in connection with cleaning the sidewalks and streets of snow, but not necessarily limited 15 to this adaption.

It is well appreciated that numerous devices have been proposed for removing foreign substances, such as snow, etc., from side walks and streets. These devices have 20 for the most part been in the nature of a power driven scraping means, which necessarily involved considerable expense in operation, aside from the fact that the foreign substances were not, for the most part, efficiently removed.

30 A further defect experienced in connection with devices of this nature has been that the vehicle, or similar device utilized for supporting the cleaning element has usually been supported by wheels, which wheels necessarily moved through the substance to be moved, rendering the movement of the vehicle or similar device very difficult.

With this in view we have constructed a 35 street cleaner, which as aforesaid is particularly adapted for use in connection with snow removal, but not necessarily limited to this adaption, and which primarily, may be manually operated, so that the expense incidental to devices of this type heretofore experienced may be eliminated.

40 A further object of our invention is the construction of a device of this nature which shall effectively clean the entire surface over which the same is moved.

45 A still further object of our invention is the construction of a cleaner in which the supporting medium forming a part of the device will move in the path which has been cleaned by the cleaning element, aside from cleaning the surface over which it is moved, moving the foreign matter to one side.

Further objects of our invention will appear in the annexed specification and draw-

ings, which latter illustrate one practical embodiment of our invention, and in which—

Figure 1 is a plan view, and
Fig. 2 is a side view of a cleaner constructed in accordance with our invention.

In these views, the reference numeral 5 indicates the handle, which may conveniently be provided to permit of a manual movement of the frame 6, which is attached to the lower end of the handle.

A rotatable member, conveniently including a shaft 7, mounting radially extending bristles 8, is now provided, and positioned in advance of the main portion of the frame 6, by being mounted in bearings 9 conveniently forming an integral extended part of the frame 6.

It will also be seen that the body of the brush 8, lies at an angle to the path of travel of the cleaner, thus removing any foreign substance, with which it contacts, all to one side of the cleaner. This disposition of the brush is accomplished by extending the frame, as has been indicated by the reference numeral 10, to project beyond the opposite portion 11 of the frame. Both of these extended portions of the frame, terminate as aforesaid, in bearings 9, and it is to be noted that these bearing portions carry the shaft 7 in such a manner that the brush will be moved forward at an angle to the direction of travel of the cleaner.

Supporting wheels 12 are rotatably secured to the frame 6, and serve by any suitable transmitting mechanism, such as 13, to effect the rotation of the shaft 7 forming part of the brush. Thus, we have provided a cleaner, the cleaning element of which will primarily move in front of the supporting medium, thus providing a clear path for the latter, and permitting of its more ready movement.

Also the simple construction provided will permit of the effectual manual operation of this cleaner, and will serve to transmit any movement on the part of the supporting wheels 12 to the cleaner element.

In this connection it is to be noted that a secondary supporting element, conveniently including a wheel 14 may be provided to one side of the frame 6, and adjacent the extended portion 10 thereof, for more evenly balancing the weight of the entire device.

It will also be appreciated that particles

of snow may cling to the bristles of the brush, and be thrown back upon the surface cleaned, thereby, and to eliminate this, the outer ends of the extending portions 10 and 11 of the frame mount a scraper 15, adapted to contact with the bristles 8 to effectually remove any adhering particles of snow therefrom.

Obviously numerous modifications of structure might readily be resorted to without in the least departing from the spirit of our invention, which we claim as—

A cleaner including a frame, non-alined wheels mounting and balancing said frame,

a shaft journaled to said frame, a cleaning element encircling said shaft, bevel gears mounted to each end of said shaft, bevel gears associated with said frame and meshing with said first-mentioned bevel gears, sprocket wheels associated with said last-mentioned bevel gears, further sprocket wheels associated with each of said non-alined wheels, and driving chains connecting said sprocket wheels adapted to drive said cleaning element on both ends.

JOSEPH PANTALEONE.
MICHAEL ZODA.
